VACUUM TUBE

Andrew Ernest Lyle, Cambridge, Mass., assignor
to Raytheon Production Corporation, Newton,
Mass., a corporation of Delaware

Application July 25, 1929, Serial No. 381,018

8 Claims. (Cl. 250—27.5)

This invention relates to vacuum tubes and methods of manufacturing the same. In the manufacture of vacuum tubes, especially of the kind used in radio receiving sets, it is customary to assemble the electrode structure on supporting wires sealed in a press. If at any stage of the assembly anything goes wrong, the entire assembly must be discarded. Thus in the case of a finished tube a defective seal necessitates discarding the entire structure.

In addition, the presence of the bulky glass press with its depending stem at one end and the projecting supporting wires at the other end makes the task of assembling inconvenient, slow and expensive. The presence of the glass supporting structure as well as the wires is not conducive for quick and easy manipulation of the assembly in welding machines. Furthermore, in assembling on the supporting wires sealed in the glass press, operators often force and strain the supporting wires out of their natural position to dispose them in some particular relation and in doing so are apt to cause minute cracks at the seals producing latent defects which become noticeable when the entire tube is finished and is being tested.

In the manufacture and assembly of a tube in which more parts are required than in the ordinary three element tube, all of the above disadvantages and problems become sharply accentuated. Thus in the manufacture of a shield grid tube, especially one having an equi-potential cathode, the number of parts to be assembled becomes so large and the work becomes so difficult that the presence of the glass press and supporting wires sealed therein results in an objectionable expense particularly in quantity production of such devices. In the manufacture of these tubes, the number of defective tubes present when testing is so large that the amount of material discarded becomes an item of large proportions.

An object of this invention is to devise a tube in which the electrodes may be assembled as a unit independently of the press and supporting wires and when completely assembled may be conveniently and easily disposed on the supporting wires sealed in the press. With such a tube if a defect appears on test, the assembly may be easily removed from the supporting wires and either one or the other member salvaged for later use.

A further object is to devise a tube which may be manufactured and assembled in a convenient, expeditious and cheap manner with a resultant

increase in efficiency and uniformity and a decrease in cost of manufacturing. Another object of this invention is to devise a tube which shall be sturdy and inherently self-supporting to maintain the electrodes rigidly in their initial predetermined relative position. An additional object is to devise a tube having more than the usual three electrodes and which may be assembled as a unit apart from the press and supporting wires. An additional object is to make such a tube with the additional electrodes so compact and sturdy that the characteristics of the tube will remain substantially unchanged when subjected to severe mechanical shock. Other and additional advantages will become evident to those skilled in the art as the description proceeds.

Referring to the drawings, Figure 1 is an elevation view of a preferred form of tube completely assembled.

Figure 2 is an elevation of the electrode assembly of Figure 1 with certain portions cut away.

Figure 3 is a sectional view of the upper portion of Figure 2.

Figure 4 is a perspective view of the electrode assembly.

Figure 5 is a sectional view of the bottom of Figure 4.

Figure 6 is a view partly in section showing the cathode grid and end insulators of an electrode structure.

Figure 7 is an elevation view of the cathode and grid electrodes with a portion of one shielding grid and a bottom supporting plate.

Figures 8 and 10 are perspective views of insulators used in the electrode construction.

Figures 9 and 11 are sectional views of Figures 8 and 10 respectively.

Fig. 9a is an enlarged view of the upper left-hand corner of Fig. 3.

Fig. 9b is an enlarged fragmentary view showing a portion of the edge construction of the retaining plates used on the ends of the electrode assembly.

Figure 12 is a sectional view on 12—12 of Figure 6.

Figures 13 and 14 are perspective views with parts cut away of two modifications.

Referring more particularly to Figure 6, within a cylindrical metal member 1 is a heating member 2 extending the full length of member 1. Member 1 forming a cathode is preferably of nickel and has its surface treated with suitable chemicals such as oxides of alkaline earth metals in order that when it is heated electron emission occurs. Heater 2 may be of any suitable mate-

rial such as tungsten, platinum or a nickel silicon alloy and is preferably spaced from member 1 throughout its entire length. If desired, heater member 2 may have its surface covered with a 5 protecting insulating layer of kaolin or any other refractory material in order that no short circuits will occur in case the metal wall of 1 contacts with the coils of the heater. Leads 4, 5, and 6 are provided for the equi-potential cathode 10 and heater respectively. The entire heater structure including the equi-potential cathode, heater and supports is more fully disclosed in my copending application, Serial No. 315,275, filed October 26, 1928.

15 The bottom of the cathode structure is suitably supported by an insulating member of lava or similar material. This insulating member comprises a circular portion 7 and an elongated base portion 8. As shown clearly in Figures 4-7 20 inclusive, insulator portion 7 is provided with apertures through which leads 4 and 6 of the cathode and heater respectively project. The other end 5 of the heater projects from the opposite end through the center of a disk 10 of mica, lava or 25 any other desirable insulating material.

Between the two insulators is supported a control grid comprising a helical wire 11 supported by diametrically opposed wires 12 and 13. This 30 grid is made by well known machinery in the customary manner providing a structure which firmly maintains the coils of wire 11 on wires 12 and 13.

Wires 12 and 13 project through suitable apertures in insulator 10. The bottom ends of 12 and 35 13 are preferably short enough so that they do not go beyond insulator 8 but fit into depressions in insulator 7, as shown in Figure 12.

The described electrode assembly is suitably supported at its lower end by dish shaped member 15. This member has a centrally disposed aperture bounded by an upstanding flange 16 adapted to fit around the periphery of cylindrical insulator 7. Adjacent the flange 16 are two apertures 17 and 18 into which project wires 19 and 40 20. These wires support a helical shielding grid 22. As shown in Figure 7, wires 19 and 20 project through suitable apertures in insulator member 10. Wires 19 and 20 projecting through apertures 17 and 18 of plate 15 engage apertures 23 45 and 24 of base 8 of insulator 7 and maintain the insulator in position by having the free ends of wires 19 and 20 bent over or suitably arranged so that the wires will not pull back through the insulator and plate. It is evident that wires 19 and 20 pass through and directly engage plate 50 15 and thus make contact therewith.

Insulating member 10 at the top of the assembly is suitably supported by a dish shaped member 25. This member may have a centrally disposed depressed portion 26, which portion has a central aperture bounded by a flange 27. The diameter of flange 27 is such as to fit shielding grid 22 and be engaged thereby to help support the latter. Disposed at diametrically opposing 60 positions in plate 25 are two bosses 29 pressed out from the plate when it is stamped. It will be noted that these bosses are stepped and comprise circular central portions 30 supported by small flanges which go into almost annular portions 31. Portions 31 are surrounded by flanges and merge into member 25. These bosses cooperate with two similarly disposed bosses on the bottom plate 15 to support insulators and wires for the maintenance of an anode electrode 37. 65

75 As is well known, in a shield grid tube the

shielding grids are around the anode and between the grid and the anode and as a rule shield the ends of the electrodes. In this construction it is necessary to insulate the anode electrode and its supporting members from the two end dish shaped members 15 and 25 respectively. The insulation from plate 25 is accomplished by two insulating members 32 comprising a cylindrical portion 33 and a circular base portion 34. This is shown in Figures 8 and 9.

10 Portion 34 of insulators 32 which may be of lava or any other similar material, fit and are centered by portions 30 of bosses 29 of plate 25. In order to maintain the insulators in place at all times, I preferably slip over portion 33 of the 15 insulators, metal washers 35 which are welded to member 25. These metal washers are preferably of such a size and shape as to fit portions 31 of bosses 29. In this way, it is evident that insulators 32 are maintained in desired relationship 20 with plate 25.

Dish shaped member 15 as previously pointed out has two diametrically opposing bosses 38. These bosses are similar to bosses 29 of plate 25 with the exception that the very centers of the 25 bosses are punched out leaving apertures 39. Insulators 40 comprising a cylindrical portion 41 and a base portion 42 and having aperture 43 shown in Figures 10 and 11 are suitably disposed in the bosses in precisely the same manner as 30 insulators 29, namely, by the provision of metal washers 35 clamping the insulators in the bosses and maintaining them in fixed relationship. Between the two end members 15 and 25 is disposed an anode or plate electrode 37 preferably of metal 35 gauze. This is a circular electrode and is supported by diametrically opposing wires 44 and 45 welded thereto. The upper ends of these wires fit into holes in insulators 29 disposed in member 25. The lower ends of wires 44 and 45 are 40 suitably supported by insulators 40 and project therethrough to the outside of the entire assembly. The diameter and length of anode 37 are such that the edges of the anode rest upon portions 33 and 41 of insulators 32 and 40 respectively. It is evident that the anode is thus thoroughly insulated from the two end dish members.

45 Dish shaped members 15 and 25 have their extreme peripheries bent to form flanges 46. At a plurality of spots of each of these members, 50 ears have been cut out and the edge distorted for a purpose to be later described. It will be noted that at the inner edges of flanges 46, troughs 47 have been formed. Into both troughs fit the edges of electrode 48 which may be of 55 gauze or solid metal. This electrode is the shielding electrode surrounding the anode and is tightly held by the two end members 15 and 25. Flanges 46 cover and form a protecting rim for the edges of electrode 48 to maintain it in shape and in 60 position. If desired, the flanges and electrode may be welded together at several spots.

To provide a lead to the bottom of the assembly for end 5 of heater member 2, apertures may be punched out in plates 15 and 25 at registering 65 points at any convenient position and insulators 49 disposed therein. A wire 50 may be threaded through and crimped at each end in order to retain it in place. A short connecting wire 51 may then be welded from 5 to 50 to provide a 70 through connection. Preferably the apertures in each of the members are so disposed as to bring wire 50 outside of anode 37 and inside of electrode 48. If desired, heater 2 may be a double helix with both leads through insulator 7. 75

In order to more thoroughly shield the control grid a metal member 53 may be fitted over portion 8 of insulator 7 where it lies against the outside surface of dish member 15. This member is provided with an opening or slot 54 for leads 4 and 6, and may be welded to the ends of wire 19 and 20 of the shield grid at ears 21 punched out therefrom and allowing the wires to protrude.

It is evident that the entire electrode assembly forms a compact rigid and unitary construction. Because of the shaping of various parts, the parts fit together and tend to adjust themselves into correct position. By means of leads 4 and 6 as well as wire 50, connection to the cathode and heating circuit may be established. Either one of wires 44 and 45 may be chosen as a lead for connection to the plate circuit. Either one of wires 12 or 13 projecting through top insulator 10 may be chosen as a connection for the control grid while connection to the shield grid may be made at any point on the metal enclosing structure.

To maintain the assembly firmly in place, I preferably crimp or weld tiny pieces of metal to various protruding free wire ends after assembly. The top of wire 19 protruding beyond insulator 10 is thus provided with a small piece of wire 19' welded to it. Thus the various wires projecting beyond insulator 12 may be crimped or suitably enlarged just beyond the insulator to prevent the parts from falling apart in the course of assembly.

In order to mount the entire assembly on a press, the peripheries of dish members 15 and 25 are provided with a plurality of projecting portions 55. These portions have small ears 56 punched out therefrom forming apertures 57. The apertures on both the opposing members 15 and 25 register. The entire electrode assembly is suitably supported by slipping it over a plurality of wires 57' which are threaded through apertures 57 of the assembly. Preferably these supporting wires 57' which are here shown as four in number, although obviously any other number may be chosen, are sealed into a press 100 preferably having a cruciform cross section as more fully described and claimed in the pending application of Paul T. Weeks, Serial No. 306,398, filed September 17, 1928.

50 This press has the various supporting wires sealed therein which are bent to meet the apertures of the electrode assembly. If desired, the press might be of such dimensions as to allow the use of straight supporting wires sealed into the corners of the glass. Additional wires 101, 102, 103, 104 are sealed in the intermediate portion of the press and are for the purpose of connecting with the heater, cathode and plate circuits.

It is evident that any two diametrically opposed wires of the supporting wires sealed in the press might be cut off short and used as connections to the cathode grid or anode, thus reducing the number of wires necessary to be sealed in the central portion of the press. This would leave 65 two diametrically opposed wires to support the entire electrode assembly. It is also possible to insulate three of the supporting wires from the shielding structure and use these for other connections.

70 The entire electrode assembly is suitably disposed in the usual glass tube 58 having the well known base 59 provided with standard prongs 105 for engagement in the standard socket. For the particular type of tube shown, five prongs 75 will be necessary, one for the equi-potential

cathode, two for the heater, one for the plate electrode and one for the shielding structure. The connections to the heater circuit are made by means of wires 101 and 102 connected to the leads 50 and 6 of the heater. Wire 103 connected 5 to lead 4 of the cathode forms the connection for the cathode, while wire 104 connected to standard 45 of the plate forms the plate connection. The wires 101, 102, 103, 104, and one of the standards 57' are each connected respectively to one of the 10 prongs 105. The connection for the shielding structure may be very easily obtained by extending one of the supporting wires 57' through the seal to one of the prongs. Connection to the control grid may be made by means of wire 6 15 welded to either one of the upper free ends of wires 12 and 13 of the control grid. This wire is sealed through the top of the tube and is soldered to a metal cap 62 cemented to the glass.

In the actual manufacture and assembling of the various electrodes, insulators and parts, the two end plates 15 and 25 are provided with their insulators 32, 40 and 49 maintained in place by metal washers welded to the plate members themselves. Shield grid 22, anode 37 and outer 25 electrode 48 are then suitably positioned with respect to the two end plate members, the top and bottom ends of wires 19 and 20 being threaded through apertures formed in both of the end plate members and the other wires being 30 threaded through or engaging their respective insulators. Flanges 46 are then suitably welded to outer electrode 48 at a plurality of spots. Wire 50 may be crimped at both ends where it emerges from the insulators. The resulting 35 structure is sturdy and rigid enough to maintain itself against all reasonable strains.

The cathode and control grid assembly may then be very simply inserted by removing insulating disk 10 of the assembly shown in Figure 6 40 and sliding the cathode and grid up inside of the shield grid. Apertures 23 and 24 of insulator 8 are aligned with the bottom of wires 19 and 20 of the shield grid projecting through bottom plate 15. All that is necessary is to thread lead 5, top 45 ends of wires 12, 13, 19 and 20 through insulator 10 and push this down against the top of plate member 25. As soon as this is done the top ends of any one or all of the projecting wires may be suitably crimped or have a small piece of metal 50 welded to maintain the insulator in place. Wire 51 may thereupon be welded to connect lead 5 and wire 50 of the heating circuit. Shield 53 may then be slipped over the bottom of insulator 8. The bottom ends of wires 19 and 20 will project 55 through apertures punched in this shield and may be welded to ears 21 formed in the shield when the apertures are punched out.

It will thus be seen that I have devised a tube 60 which may be very easily and cheaply assembled separately from the glass press and supporting wires. It is obvious that the assembly itself is a rigid unit which does not depend upon the press or supporting wires for the maintenance of the relative positions of the respective electrodes. When the tube is finished and tested it is evident that if the press is found defective, the entire tube assembly may very easily be salvaged 65 by pulling it from the supporting wires. In order to make salvage more expeditious, I prefer to weld only some of the ears 56 to the various supporting wires leaving others free. In case the structure must be pulled off, the welded ears may very easily be clipped off leaving other ears for welding purposes. It is obvious that the ears are not 70 75

necessary since the supporting wires may be welded to members 15 and 25 at the apertures.

- By this construction it follows that if the cathode structure or control grid are defective in any manner, they may very easily be replaced by clipping one or more of the wires which have been crimped or have had small pieces of metal welded to them to maintain insulators 7 and 10 in place. In order to make such a change easier, it is possible to crimp or weld a small piece of metal to the top ends of either one or both of the control grid wires 12 and 13 and leave the other wires free. It is a very simple matter to clip ears 21 and pull the cathode and control grid assembly right out from the electrode assembly. In this way the cathode and grid portion of the electrode assembly may be salvaged if the rest of the assembly is defective or may be replaced if defective itself.
- If desired only the extreme ends of the cathode heater leads 4 and 6 may be adapted to maintain the insulators together. It is evident that shield 53 may be omitted and wires 12 and 13 of the grid project through the bottom of insulator 8. In such a case, the ends of these wires may be used to maintain the insulators in place.

Referring to Figure 13, a structure somewhat similar to the previously described structure is shown with the exception that only three electrodes are present. The cathode 1 has a grid 11 supported by wires 12 and 13 in substantially the same manner as shown in Figures 6 and 7. The bottom insulator 7 may be the same as in Figure 6 and is disposed in substantially the same manner with respect to a bottom member 75. The upper ends of cathode and grid project through an insulating disc 10 of mica or the like which rests on an apertured member 76 similar to the member in the preceding modification. Between dish members 75 and 76 is an anode 77 supported in substantially the same manner as the outer electrode of the shield grid assembly. The entire assembly has the customary ears and apertures for detachable positioning on supporting wires of a press. It is evident that in order to standardize on parts, dish shaped members 75 and 76 might actually be the same as members 15 and 25 of the shielded grid structure. In such case there would be no necessity for disposing the extra insulators and electrodes within the structure.

In Figure 14, I have shown another modification in which the two end members are insulators and in which the cathode is of the filamentary type. In this modification a V shaped cathode 80 has its ends suitably supported at clips 81 and 82 fixedly positioned in an insulator member 83. The apex of the V is firmly maintained in position by spring member 84 in the upper insulating plate 85. A helical grid 86 is suitably supported between wires 87 and 88, the latter projecting through suitable apertures in members 83 and 85. These wires may be crimped as at 88' in order to maintain insulating members 83 and 85 against each other. Surrounding the grid 86 is a rectangular anode 90 which may be fabricated from four blanks and curled at the corners as shown at 91 in the usual manner. The anode preferably has small ears 92 which project through slots 93 in insulating plate 83 and 85. These ears are bent flat and tend to anchor the end plates firmly against the electrodes.

It is evident that because of the rigidity of anyone of the electrode assemblies it is unnecessary to do more than to support the entire weight of the assembly. In prior devices it has been cus-

tomary to seal a large number of supports in the press for supporting various electrodes and glass leads with respect to each other. As a rule, these were useless as leads and because of the large number of wires sealed in the press greatly increased the probability of leakage in the seals. With a structure like that shown in Figure 14 it is possible to thread supporting wires to suitable apertures in plates 83 and 85 while welding connecting wires from these supporting wires to the various electrodes. In the case of the structure of Figure 13 and of the other figures, it is very simple to insulate one or more of the supporting wires from the metal shielding structure. In order to do this the insulator shown in Figures 10 and 11 may be very effective in apertures 57 of the end members. In the constructions of the prior art such an efficient use of supporting members as leads was practically impossible since the supporting wires were directly welded to the various electrodes. To insert insulators between the supporting wires and the electrodes was burdensome and expensive.

It is evident that the circular electrodes of the structure shown in Figures 2 and 4 as well as in Figure 13 may be rectangular as in Figure 14. It is also evident that the end members of insulating material in Figure 14 may be circular and have circular electrodes between them as shown in Figure 13. It is obvious that cathode 1 of Figure 13 may be very simply replaced by a filamentary cathode.

My invention is characterized by the broad feature of an electrode assembly which may be removed or replaced as a unit on the press of a vacuum tube. In addition the assembly itself includes a portion which may be very simply removed as a subsidiary unit to replace defective or undesirable parts. In its broader aspects my invention is characterized by the provision of a plurality of electrodes, the ends of which are firmly maintained with respect to each other to make a unitary compact structure. More specifically the ends are supported by members which may if desired be flat or circular or metallic. The outermost electrode has its edges firmly maintained by end engaging members.

In another aspect my invention is characterized by the fact that the ends of some electrodes engage insulators to maintain them in position and that there are means for maintaining all of the electrodes in desired relative position to each other and the insulators and said means cooperate in such a manner that the insulators maintain said means in desired relative position to each other. The means which will maintain the insulators together will maintain the entire assembly intact. The ends of anyone or more of the electrodes piercing said insulators may thus carry at their extreme ends the means for maintaining the entire electrode assembly intact.

I claim:

1. An electrode assembly comprising a cathode, a grid surrounding said cathode, insulators engaging both ends of said electrodes and maintaining them in desired position, an anode surrounding said grid, two flat metal members at each end of the anode and engaging said insulators, said flat metal members being provided with a plurality of recesses, additional insulators mounted in said recesses, said insulators insulating said anode from said flat members.

2. An electrode assembly comprising a cylindrical cathode, a heating member within said cathode, a grid surrounding said cathode, a shield

5 electrode surrounding said grid, an insulator at each end of said electrode maintaining said electrodes in desired relationship to each other, an anode surrounding said shield electrode, and an additional electrode surrounding said anode, a pair of metal members engaging each of said insulators, means for insulatingly supporting said anode between said pair of metal members, and means for maintaining said metal members in desired relationship to each other.

10 3. In an electrode assembly whereby a cathode, grid and anode are maintained as a rigid independent unit, a metal plate provided with a plurality of bosses, insulators set into said bosses, and metal washers maintaining said insulators in said bosses.

15 4. An electrode assembly comprising an indirectly-heated cathode, a grid surrounding said cathode, a shield electrode surrounding said grid, an insulator at each end of said electrodes maintaining said electrodes in desired relationship to each other, an anode surrounding said shield electrode, and an additional electrode surrounding said anode, a pair of metal members engaging said insulators, means for insulatingly supporting said anode with respect to said pair of metal members, and means for maintaining said metal members in desired relationship to each other.

20 5. An electrode assembly comprising an indirectly-heated cathode, a grid surrounding said cathode, an insulator at each end of said electrodes maintaining said electrodes in desired relationship to each other, an anode surrounding said grid, and a pair of metal members engaging said insulators, means for insulatingly supporting said anode with respect to said pair of metal

members, and means for maintaining said metal members in desired relationship to each other.

6. A space discharge device comprising a cathode, a grid surrounding said cathode, a shield electrode surrounding said grid, an insulator at each end of said electrodes maintaining said electrodes in desired relationship to each other, an anode surrounding said shield electrode, a pair of metal plate members engaging said insulators, said anode being insulatingly supported by said pair of metal plate members, and means for maintaining said metal plate members in desired relationship to each other.

10 7. A space discharge device comprising a cathode, a grid surrounding said cathode, a shield electrode surrounding said grid, an insulator at each end of said electrodes maintaining said electrodes in desired relationship to each other, an anode surrounding said shield electrode, a shielding member surrounding said anode, a pair of metal plate members engaging said insulators, said anode being insulatingly supported by said pair of metal plate members, and means for maintaining said metal plate members in desired relationship to each other.

15 8. A space discharge device comprising a cathode, a grid surrounding said cathode, a shield electrode surrounding said grid, an insulator at each end of said electrodes maintaining said electrodes in desired relationship to each other, an anode surrounding said shield electrode, a pair of metal plate members engaging said insulators, said anode being insulatingly supported by said pair of metal plate members, said metal plate members being electrically and mechanically connected together.

20 25 30 35 ANDREW ERNEST LYLE.
